CLAIM

The ornamental design of a paper towel dispenser assembly, as shown and described.

DESCRIPTION

FIG. 1 is a top and front perspective view of a paper towel dispenser assembly showing my new design;
 FIG. 2 is an enlarged front elevational view thereof;
 FIG. 3 is an enlarged top plan view thereof;
 FIG. 4 is an enlarged rear elevational view thereof;
 FIG. 5 is an enlarged left side elevational view thereof;
 and,
 FIG. 6 is an enlarged right side elevational view thereof.
 The broken-line disclosure of a paper towel roll in the views is for illustrative purposes only and forms no part of the claimed design.
